ICE SCRAPER

Irving W. Jorgensen, P.O. Box 191, Owosso, Mich.

Filed June 27, 1958, Ser. No. 51,569

Term of patent 14 years

(Cl. D9—6)

Fig. 1 is a view in perspective of an ice scraper showing my new design;

Figs. 2 and 3 are respectively, rear and front elevational views thereof;

Fig. 4 is a bottom plan view thereof; and

Fig. 5 is a view in section taken along the line 5—5 of Fig. 3.

The dominant features of my design reside in the portions shown in full lines.

I claim:

The ornamental design for an ice scraper, as shown and described.
